YARN BINDER FOR KNITTING MACHINES

Robert H. Lawson, Pawtucket, and Augustin Gagné, Central Falls, R. I., assignors to Hemphill Company, Central Falls, R. I., a corporation of Massachusetts

Application October 3, 1938, Serial No. 232,928

8 Claims. (Cl. 66—134)

This case concerns a mechanism and method of feeding yarn to needles of a knitting machine and a binder and cutter functioning with the feeding means. More especially, the feeding means and the binder and cutter are to be employed with independent needle machines of the circular type wherein a yarn change is to be made within a course or within courses, and wherein the end of the yarn withdrawn is to be cut short and also the end to be introduced to the needles maintained as short as practicable.

In the figures of drawings:

Fig. 1 is an elevation showing parts of the frame, clutch and controlling means for the novel elements concerned;

Fig. 2 is an elevation showing parts in Fig. 1 as seen from the right hand side of the machine;

Fig. 3 is an elevation, parts being broken away and the main shaft being shown in section wherein certain of the controlling means are illustrated in greater detail;

Fig. 4 is an elevation showing the support for the feeding means, binder and cutter, and further detail of the controlling means for the yarn feeding mechanism;

Fig. 5 is a sectional view showing part of the support, the binder and cutter, and the means for periodically actuating the same;

Fig. 6 is a plan showing a fragment of the sinker ring, cam means thereon, and the actuating means for the binder and cutter;

Fig. 7 is a plan showing part of the needles, sinker ring, supporting bracket and the feeding means and binder and cutter thereon, the feeding means being in a position in which it has just introduced the yarn to the needles.

Fig. 8 is a similar view showing only a fragment of these parts but wherein the yarn has been withdrawn and is held in the binder;

Fig. 9 is an elevation showing controlling mechanism for the yarn feeding means;

Figs. 10 and 11 show this controlling mechanism in greater detail;

Fig. 12 is a view similar to Fig. 8, but illustrates the entire support, binder and cutter and feeding means withdrawn to an inactive position;

Fig. 13 is a section showing the yarn feeding means and its relative position between the sinker cap and the latch ring;

Fig. 14 is a diagrammatic view showing needle cams and the path of needle butts through those cams;

Fig. 15 is a section showing needles passing the mouthpiece and the relative position of the yarn

feeding finger and the binder and cutter with respect to those passing needles;

Figs. 16 is a section taken longitudinally through the binder and cutter;

Fig. 17 is a view showing the binder and cutter in elevation, the support being shown in section; and

Figs. 18 through 26 are detailed views showing separate parts of the binder and cutter.

In certain circular, independent needle knitting machines it is common practice to reinforce areas such as the high splice or the sole of stockings knitted therein, this reinforcing being accomplished by feeding an additional yarn to a segment of needles while another yarn or yarns are fed to all needles. This additional yarn is desirably to be fed in such a way that it starts knitting on the same needle and is withdrawn at the same needle, or, is fed and withdrawn at substantially the same needle. Furthermore, it is desirable to introduce the yarn in such a way and by such mechanism that the end of the yarn pulling from the binder will be as short as possible. Likewise when withdrawn and cut, it is desirable to cut as close to the last needle knitting as is possible. If this desired result is accomplished the resulting product will not be characterized by long undesirable ends of the reinforcing yarn projecting to such a degree as will necessitate a separate float cutting operation. This is a saving of time and expense and the resulting product is one much more salable than would otherwise be the case.

Referring to the figures of drawings, Figs. 1, 3, 4, 7, and others, the frame of the machine 1 has a base 2, a needle cylinder 3 carrying a sinker supporting ring generally indicated at 4. A yarn lever bracket 5 is mounted at the base and carries the usual yarn change levers 6 which are connected by control wires 7 to cams on a drum 8 rotatable with the main cam shaft 9, a full description of these parts being found in Hemphill Patent 993,443. Latch needles 10, Fig. 15, are movable within the usual slots in the cylinder and take yarn at a mouthpiece within a latch ring 11 of more or less conventional construction, Figs. 12 and 15. The additional or reinforcing yarn is to be fed adjacent the mouthpiece in this latch ring and close to the other yarn or yarns being fed from a yarn lever or levers 12—16 which are controlled by mechanism previously referred to. The yarns fed through these levers 12—16 are retained and cut in a main binder and cutter located within the needle circle as is the common practice in Banner machines. The reinforcing

yarn is fed by a yarn feeding finger which is swung more or less horizontally, although it has a deliberate component of movement vertically, which moves from a position external of the needle cylinder to a position where it would just about overlap the needle circle. The binder and cutter is of the external type in contrast to the main binder and cutter referred to, and when in active position, projects slightly over or within the circle of needles. These parts are located just behind the mouthpiece and main yarn feeding levers 12-16 when considered in the direction of rotation of the needles. Obviously, if the needle cylinder were stationary and the feeding means rotatable with respect thereto, the reverse would apply.

Referring to Figs. 3, 5, 7 and others, a bracket 17 has a base 18 by means of which it is adjustably attached to the base of the machine. This bracket terminates at the top in a flat portion 19 on which a supporting plate 20 is capable of being swung about a pivot 21. The plate 20 is of a shape and extent sufficient to support both the feeding means and the binder and cutter. Its movement is restrained by a shoulder screw 22 which is engageable within a slot 23 in the plate. The plate is normally swung about the pivot 21 in a direction to move the entire assembly toward the circle of needles by a spring 24, Fig. 4. A bell crank lever having an upwardly projecting arm 25 is pivoted at 26 to the side of the bracket 17 and connects at its other arm 27 through a link 28, connecting coupling 29, Figs. 1 and 2, a link 30 and a lever 31, to be actuated by certain cams 32 and 33 on the drum 34 also fixed to the main cam shaft 9. The arm 25 of said first mentioned lever projects through an opening in the plate 20, Fig. 7, and whenever lever 31 is moved by either of cams 32 or 33, will withdraw the plate and all attached parts away from the needle circle to a position such as illustrated in Fig. 12.

In both Figs. 7 and 12 there will be seen a stop consisting of a stop screw 25' threaded into a depending part of a plate 26' attached to the top of the swinging support 20. This screw is adjustable and when the support and attached mechanism are drawn inwardly toward the cylinder of the machine, this screw abuts against the outer side of the top flat part 19 of the post 17. This plate and all parts thereon are withdrawn except at such times as the reinforcing yarn is being fed to the fabric.

Now referring to Figs. 1, 2, 3, 4 and 7-13, the reinforcing yarn feeding means will be described in detail. The plate 20 has a downwardly depending boss 35 in which is freely mounted a spindle 36 to the top of which is fixed a lever 37. This lever 37 carries a yarn feeding finger 38 having an eyelet 39 adjacent its end through which a yarn 40 is threaded. This finger is shaped at its feeding end in the form of a hook, the pointed end 41 of which serves as a latch opener when the yarn is to be fed to needles. This spindle 36 is oscillated in its bearing in the boss 35 and is also free to slide vertically therein, but tends to be maintained in downward position by a spring 42 between the lower end of the boss and the adjustable collar 43, Figs. 4 and 9. The free end of lever 37 has attached thereto a link 44 by means of which the yarn finger 38 is swung to and from a feeding position. As shown in Figs. 4, 8 and 9, a cam 45 having a bevelled end 46 serves to raise the finger 38 slightly when it is moved away from its feeding position. That

is, as the link 44 is pulled outwardly drawing lever 37 and the yarn feeding finger to the position of Fig. 8, the finger 38 will ride up the bevelled end of this cam to be elevated to the position in Fig. 9 as contrasted with that of Fig. 4. Likewise when moved inwardly the spring 42 tending to draw the spindle 36 downwardly will maintain the yarn feeding finger 38 in its lowermost position.

10 The link 44, as clearly shown in Figs. 8 and 12, has an angular extension 47 attached at about its midpoint, this extension serving to limit movement of the link in either direction and thus to define the ultimate extents of travel of the yarn feeding finger itself. A bracket 48 attaches to the plate 20 and has two stop screws 49 and 50 threaded into bosses 51 and 52. Lock nuts maintain these stop screws in adjusted position and the extension 47 abuts against these screws as the mechanism is moved from one position to the opposite.

A bell crank lever having arms 53 and 54, Figs. 3, 4, 9 and 11, is pivoted at 55 in a bracket 56 attached to the side of the bracket 17. The arm 53 is engaged by a suitable connection to the link 44, that connection working in a slot 57 in the link. The connection herein shown as a sort of shoulder stud 58 has a hook 59 attached to it and to which is connected a spring 60. The spring 60 also connects to the extension 47. When lever 53 is swung outwardly by mechanism presently to be described, it will impart movement to the link through said spring which is under sufficient tension to draw the link and functioning parts attached thereto to the position of Fig. 8 while the shoulder stud 58 is in the forward part of the slot 57 as shown in Fig. 8. During splicing the movement imparted to the bell crank does not extend the spring beyond that point, or at least, the movement is not necessarily greater. For other purposes to be described the bell crank is given a greater movement at which time spring 60 is extended and the stud 58 moves toward the other end of slot 57.

45 For imparting the periodic feeding and withdrawing movements to the finger 38, a cam 61 mounted on main shaft 62 functions upon a follower 63 on an arm 64 fixed to a short shaft 65 and is rotatable in a bearing in bracket or lug 66 connected to the under side of the base 2, Figs. 1 and 3, the arm 64 being part of a long sleeve 67 which also carries at the end opposite the lug 66, a second arm 68. This arm 68 connects by means of an adjustable, two piece link 69 to the free end of the lever 54. As the main shaft 62 rotates once for every revolution of the needle cylinder, the cam 61 will impart movements resulting in swinging lever 38 to feeding position and withdrawing it from that position once every revolution of said cylinder. According to the extent of the cam 61 the time within which lever 38 is out of feeding position will be varied, that is, the extent of reinforcing is controlled by the extent of cam 61.

60 The cams 70 and 71 on drum 8 serve to withdraw this yarn feeding finger 38 from feeding position permanently, and, by mechanism to be described, stop the periodic operation of the binder and cutter. A lever 72 contacts said cams 70 and 71 and connects by a wire 73 to the same point of connection at the end of lever 54 to which the link 69 is attached. Whenever cams 70 or 71 are in position to engage lever 72 and withdraw the finger 38 they pull the bell crank lever having arms 53 and 54 to the position shown in Fig. 9.

That is, the spring 60 is extended and the connection 58 is in the outer end of slot 51.

The opposite extreme movement of the levers 53 and 54 is governed by a stop screw 74 which bears upon a lug 75 on the lever 68, Fig. 3. This stop screw is held in adjusted position by lock nut 76.

Now referring to Figs. 4, 5, 6, 7 and 8-12, the mechanism for actuating the binder and cutter will be described. The plate 20 carries a second boss 77 similar to the boss 35 in which is mounted for rotation and vertical sliding movement a short spindle 78. This spindle carries at its upper end an arm or lever 79 having a slot 80 in which engages a pin 81 by means of which the movable parts of the binder and cutter are caused to function. The said lever 79 has an opening through which the yarn 40 is threaded. At the lower end of said spindle 78 is fixed an element having a hub portion 82, an arm 83 and an angularly extending partial flange or fin 84. The hub 82 is fixed to the spindle by set screw 85. In the arm 83 is threaded a screw 86 having a hardened rounded head 87. This screw is adjustable to position said rounded head and is capable of being locked in any adjusted position. The sinker ring 4 carries at its lower part a cam 88, especially shown in Figs. 5 and 6, which is positioned to contact the rounded head 87 and thereby to oscillate the spindle 78 thus imparting the necessary movement to the arm 79. Normally the spindle 78 and its attached parts are held in a raised position by a spring 89. In that position the cam 88 and the rounded screw head 87 are in alignment and make contact.

Whenever the operation of the binder and cutter are to be discontinued, the said spindle 78 and attached parts are dropped to a lower position shown in Figs. 9 and 10 in which the screw head 87 is beneath the cam 88 and also beneath the edge of the sinker ring 4. This movement to lower position occurs whenever cams 70 and 71 function to draw the bell crank lever 54 to the position illustrated in Fig. 9. Whenever wire 73 is pulled downwardly as the cams 70 and 71 raise the forward end of lever 72, the extent of movement is greater than that imparted by cam 61, Fig. 3, and will bring the lever 53 against a stop screw 90 in a laterally extending projection 91 of an arm 92 pivoted upon the short pivot 55, Figs. 4, 9, and 11. A second angular type of lever has a horizontal arm 93 pivoted at 94 and a substantially vertically arranged arm 95 projecting downwardly side of the previously mentioned lever 92. A short pin or stud 96 projects from said lever 92 and engages in front of the adjacent arm 95. When lever 53 moves outwardly to a position of Fig. 9 it engages the stop screw 90, swings lever 92 until the pin 96 contacts the short depending arm 95 thus drawing down the long horizontal arm 93, the end of which engages the fin 84, Figs. 6, 9 and 10. This movement brings the spindle 78 and attached parts down to the position of Figs. 9 and 10 so that the operating means for the binder and cutter no longer function. A spring 97 attaches to a fixed part of the bracket and also to the end of lever 54 so that this mechanism is maintained in the position of Fig. 4 except at such times as cams 61, 70 or 71 are functioning to impart movements in the opposite direction.

Referring to the figures previously described and to Figs. 16-26, the binder and cutter will be described in detail. These Figs. 16-26 show the cutter in section, assembled, and separate pieces

thereof. The cutter is composed of fixed and movable parts, the fixed parts including a support in which the movable parts slide designated by numeral 98 and shown in three different views, Figs. 22, 23 and 24. This support has slots 99 by means of which it is attached to the plate 20. These slots provide for a certain amount of adjustment. The support is grooved along its length above and beneath a thin diaphragm 100. The diaphragm has a slot 101 the purpose of which will be described in due course. The support is also grooved horizontally at 102 and in this groove 102 is positioned one of the fixed binding and cutting elements 103. This piece also has a slot 104 which serves as an extension of the slot 101. The end is hooked as shown at 105 and serves to catch the yarn as it is withdrawn and as a cutting and binding edge. Another fixed piece 106, Fig. 26, attaches by screws or other suitable connections to the top of the supporting piece, the attaching means also serving to hold the element 103 in proper position. A thin, hook-like element 107, Figs. 8, 16 and 17, attaches to the offset extension 108 of the base 106. The hook 107 is made of spring material and presses against the lower and heavier hook-like element 105.

The movable parts include a slider 109, a cutter 110, spring 111 and a stop 112. The slider 109 fits above the diaphragm 100 and has projecting therefrom a pin 81, previously referred to as the projection through which movements are imparted from the arm 79 to the cutter and binder. The spring 111 is slightly curved as shown in Fig. 16 and functions beneath the diaphragm 100; these elements 109 and 111 having the stop 112 clamped between them by bolt 113. The stop 112 is of about the same thickness as the diaphragm 100 and properly spaces elements for a sliding fit.

The cutter 110 slides on the bottom hook 103-105 and forms a sort of extension of the slider 109 as it abuts against a shoulder at the forward end of the slider. The cutter edge 114 is sharpened and extends forwardly in a short hook 115 which guides the yarns as they are being cut and bound.

The stud 116 is riveted to the spring 111 and projects upwardly through the slot 101-104, through openings in the cutter and slider and serves to maintain these pieces assembled and working as a unit. Furthermore by means of an adjusting nut 117 and a spring 118 the tension on the lower spring 111 is adjusted so that the cutter will press against the fixed hook with enough force to provide proper shearing action.

As before stated this binder and cutter assembly is attached to the plate 20 and is actuated by cam 88 and mechanism heretofore described. The cam 88 is arranged and timed to open the binder and cutter before yarn lever 38 is withdrawn from feeding position. As it is withdrawn, the yarn moves away from a feeding position and outward tangentially so that it is taken within the binder being guided between the hooks 105, 107 and the cutter blade 114, at which time the head 87 of the screw 86 drops from the cam 88 whereupon a spring 119, Fig. 12, quickly closes the cutter severing the yarn and binding it as shown in said Figs. 8 and 12.

Now referring to Fig. 13, the latch ring is cut out as illustrated to allow the yarn feeding finger 38 to be swung inwardly to a point adjacent the needle circle. This cut out also allows for other parts such as the working elements which cause this finger 38 to be swung to and from feeding position. The inner end of the yarn binder and

cutter is also moved beneath this latch ring when it is in an active position. In Fig. 15 both the binder and the end of the yarn feeding finger are shown in about the position they occupy as yarn is being fed or as it is being cut and bound at each revolution of the machine. The path of needle butts is shown in Fig. 14, the usual raise cam 120 preceding the front stitch cam 121, top center cam 122, guard cam 123 and rear stitch cam 124. The needle butts travel in a pathway 125 clearing latches above cam 121, then passing down beneath cams 122 and 124 to knit. In order to allow for projecting the binder and cutter inwardly to a position adjacent the needle circle and just above passing needle hooks, the other part of the raise cam designated at 126 has a cut out portion 127 so that needle butts are raised slightly after knitting beneath the cam 124, but do not rise to the full elevation governed by the raise cams until these needles have passed the binder and cutter.

Operation

While there are certain variations, the preferred use of a binder and cutter and the accompanying yarn feeding mechanism is that of introducing a yarn such as a reinforcing or splicing yarn once during every revolution and withdrawing it once every revolution. Along with this feeding and withdrawing of the yarn it is cut and bound as close as possible to the last needle knitting, the general construction being such that the end introduced to the needles from the binder will be as short as practicable. Usually such splicing occurs at some particular part or parts of a knitted article. For example, in hosiery it is common practice to splice above the heel and in the sole throughout the continuing part of the foot from the heel to the toe. Cams 32 and 33, Figs. 1 and 2, serve to maintain the plate 20 and all attached mechanism in a completely ineffective or inactive position except when splicing is to be done. When the toe of lever 31 drops from these cams into the space indicated at 128 and 129, the plate 20 will be allowed to be moved in toward the needle circle and all the attendant parts will be in a position where they may function properly in feeding the yarn and cutting and binding the same. The space 128 would correspond to that part of the stocking in which a high-splice was being knitted while the later space 129 controls during splicing in the sole.

Cams 70 and 71, Figs. 1 and 2, maintain the yarn feeding lever 38 completely withdrawn from action except when it is desired to splice. When the toe of lever 72 drops into spaces 130 or 131, the said yarn finger will be released in the high splice and in the sole respectively. This means that cam 61, Fig. 3, will function through mechanism described in connection therewith to withdraw the splicing yarn and to project it to feeding position once during each revolution. As before stated, the extent of cam 61 determines the length of time during which finger 38 feeds its yarn. In more detail, the high part of cam 61 controls the amount of time in which the said splicing yarn is withdrawn while the period at which it feeds is governed by the arc of the cam during which follower 61 is bearing upon the low part of the cam or not raised by the first mentioned portion thereof.

Co-incidental with the dropping of lever 72, the spindle 78 is allowed to rise to the position of Fig. 5 wherein cam 88 will be effectual to work the binder and cutter periodically as the yarn is

moved to and from feeding position. Obviously precise timing of these parts is necessary so that just as the finger 38 is moved outwardly the binder will be opened whereby the yarn may be taken in the hook and thereafter cut immediately so that the end will be as short as possible. While this requires nicety of timing and in arrangement of cams, once this adjustment is obtained, the feeding and withdrawing occurs periodically each course and the cut ends left in the finished product will be short enough so that they do not knit in nor will it be necessary to cut the ends in the finished product.

The disclosure has been made with respect to one embodiment of the invention and that has been described more or less specifically. Certain changes will be evident and are contemplated as falling within the scope of the invention as originally conceived. What is new is embraced in the following claims.

It is claimed:

1. In a knitting machine the combination of 25 yarn feeding means and a binder and cutter, means for periodically actuating said yarn feeding means and other means for operating the binder and cutter, said means for actuating the yarn feeding means also being movable selectively throughout a range greater than that normally required for periodic movement of the feeding 30 means to cause the binder and cutter operating means to become ineffective.

2. In a knitting machine the combination of 35 yarn feeding means, a binder and cutter, movable means operable periodically to move said feeding means to and from a feeding position, other means operable in conjunction with the first mentioned means but independently to impart periodic movements to the binder and cutter, the construction being such that said yarn feed actuating means is movable to an extent greater than that for normally actuating the feeding means for affecting the binder and cutter actuating means whereby the latter will cease to function.

3. In a knitting machine yarn feeding means, a 45 binder and cutter, cam means operable to impart periodic movements to the feeding means and separate cam means for imparting similar movements to the binder and cutter, other cam means for affecting said yarn feed actuating means to withdraw the same to a completely inactive position and interconnecting linkage between the yarn feed actuating means and the binder and cutter actuating means movable to withdraw the latter from a position in which it will be affected 50 by the separate cam means normally imparting periodic binding and cutting movements thereto.

4. In a knitting machine the combination of 60 yarn feeding means, a binder and cutter, a movable support for both the yarn feeding means and the binder and cutter whereby the same are movable to and from operative position with respect to knitting instrumentalities, a latch ring beneath which said feeding means and the binder and cutter are to be actuated, said latch ring being recessed at appropriate positions for the 65 said feeding and binding and cutting means.

5. A binder and cutter for knitting machines including a cutting and binding element, a spring, fixed hook-like elements against which said cutting and binding element operates and means for sliding said cutting element and spring with respect to the fixed elements so as to open and close a space between the cutting element and fixed hook-like elements.

6. In a knitting machine knitting instrumental-

ties, yarn feeding means, a binder and cutter and means for imparting periodic movements to the yarn feeding means effective to cause it to move to yarn feeding position and withdraw it from that position once during each course of knitting, other means operable independently of the means for operatively moving the feeding means to and from feeding position for causing the binder and cutter to function once during each course of knitting, said means for imparting movements to the feeding means being further movable to a position wherein the feeding means will be withdrawn still farther from its active yarn feeding position and means operable upon such movement to move the binder and cutter to a position in which it will be unaffected by its operating means.

7. In a knitting machine the combination of knitting instrumentalities, a latch ring, a supporting bracket located outside the latch ring, 20 an independently movable supporting plate on said bracket, yarn feeding means and a binder

and cutter operatively positioned upon said independently movable plate and means for moving said plate to withdraw it and the binder and cutter from active position with respect to a group 5 of knitting instrumentalities.

8. In a knitting machine the combination of knitting instrumentalities, a binder and cutter, means for feeding yarn to the instrumentalities operable to feed its yarn and to withdraw the same periodically, a latch ring, a supporting bracket outside the latch ring and an independently movable plate carried by said bracket and so constructed as to support the binder and cutter and feeding means, and means for moving said supporting plate toward and away from the instrumentalities whereby the binder and cutter and periodically movable feeding means are removed from operative relationship with the instrumentalities.

ROBERT H. LAWSON.
AUGUSTIN GAGNÉ.
